UNITED STATES PATENT OFFICE.

GEORGE HARTMAN, OF CINCINNATI, OHIO, ASSIGNOR OF TWO-FIFTHS TO
EDWARD WENNING, OF CINCINNATI, OHIO.

PAPER-BAG MACHINE.

No. 823,776.

Specification of Letters Patent.

Patented June 19, 1906.

Application filed July 28, 1905. Serial No. 271,576.

To all whom it may concern:

Be it known that I, GEORGE HARTMAN, a citizen of the United States of America, and a resident of Cincinnati, county of Hamilton, 5 and State of Ohio, have invented certain new and useful Improvements in Paper-Bag Machines, of which the following is a specification.

My invention relates to a machine for making satchel-bottom paper bags, and its object is an automatic means for keeping the tension upon the paper as it is fed from the roll uniform, a means for preparing the surface of the paper for receiving the glue, and printing mechanism inserted in the device for printing the bags prior to the time at which the folding of the bottom is completed, and means for presenting a dry surface to the bags as they leave the printing-rolls, and an improved mechanism for folding over the longitudinal flaps of the bottom. These objects are attained by the means illustrated in the accompanying drawings, in which like parts are indicated by similar reference-letters wherever they occur throughout the various views.

Figure 1 is a diagrammatical side elevation of the operative parts of a machine embodying my invention, the gearing for conveying the motion throughout the various shafts being omitted, since it is of ordinary construction and its inclusion would serve to complicate the views. Fig. 2 is a plan view, upon an enlarged scale, of a strip of paper folded and notched at intervals. Fig. 3 is a plan view of the paper blank, showing the successive steps in forming the bag. Fig. 4 is a detail horizontal sectional view taken upon line X X of Fig. 1. Fig. 5 is a transverse sectional view taken upon line 5 5 of Fig. 4. Fig. 6 is a detail view of one of the fingers for folding the paper strip into a tube. Fig. 7 is a view, partly in elevation and partly in section, of the rolls for severing the blank from the tube. Fig. 8 is a side elevation of the roll shown in Fig. 7. Fig. 9 is a detail side elevation of the arm for feeding the blank from the creasing-rolls to the printing-rolls. Fig. 10 is an end view of the arms shown in Fig. 9. Fig. 10' is a detail end view of the fingers, one of which is shown in Fig. 6. Figs. 11 and 12 are respectively side ele-

vations and end views of the cylinder against which the printing-rolls bear. Figs. 13 and 14 are respectively side and end elevations 55 of the cylinder for longitudinally slitting the end of the paper blank. Figs. 15 and 16 are similar views of the glue-foot. Figs. 17 and 18 are similar views of the creasing members for making transverse creases across the flaps. 60 Fig. 19 is a detail side elevation, upon an enlarged scale, of the rolls for folding the flaps and turning them down upon the end of the blank. Fig. 20 is a detail plan view of the complete bag. Fig. 21 is a detail perspective 65 view of the cylinder with the moving surface to contact the bag-blank after it has left the printing-rolls. Fig. 22 is a detail sectional view of the moving of the cylinder. Figs. 23 and 24 are detail side and end elevation of 70 the rolls for fluting the open end of the blanks. Figs. 25 to 27 are detail views of the box provided with means for moistening a blank.

A general description first will be given and then a detail of the operative parts.

Referring to Fig. 1, the paper is led from the roll A, over rollers a and a', past motors B and B', both of which are supplied with splines for fraying the surface of the paper. From roller a' the paper passes through the 80 box C, wherein the paper is moistened by steam. Thence the paper passes between rollers D D', where one edge is supplied with glue from the vat D'. The knife E puts notches a² at intervals in the paper. Shoes 85 F and F' fold the paper preparatory to its passing under the rolls G and G', which form it into the tube. Thence the tube passes through the knives H and H', which put the transverse slits a³ in the tube, almost severing it. From the knives the tube passes between the fluting-rolls J, which flute the end of the blank, which form the open end of the bag when completed. The blank is severed by the fluting-rolls and is grasped by the 95 swinging arm K, which carries it to the impression-cylinder L. It goes past the printing-rolls M, of which there are four shown, so that the bag may receive four different colors. The blank passes thence past the cylinder P, 100 the surface of which is supplied with a changing surface of cord to prevent accumulation of ink. Cylinder R has knives which put the longitudinal slits a⁴ in the blank, and the sta-

tionary blade opens the end of the blank and forms the diamond folds a^5 , as shown in the right-hand figure of Fig. 3. Then the glue-foot T supplies the flaps with glue, as shown by shaded lines upon the right of Fig. 3, from the vat T'. The blank is then carried along between the belts U and U'. The blades V and V' put the transverse creases a^6 , as seen in Fig. 3, in the blank and the swinging blade W folds over the longitudinal flap a^7 before the blank reaches the rolls Y Y, which fold the longitudinal flap a^8 down over the longitudinal flap a^7 and complete the bag.

A detailed description of the parts will now be given. In order that the paper may be held in proper tension, it is necessary to use some means of equalizing the decreasing strength of the pull upon the roll A due to the ever-decreasing size of the roll as the paper is unwound therefrom. This consists of the following mechanism: On a shaft a^9 , upon which the roll of paper A is wound, is mounted a wheel a^{10} , (shown in Fig. 4,) against which a brake-shoe a^{11} bears with a force which decreases the pressure of the shoe a^{11} as the roll gets smaller. This is effected by means of the coil-spring a^{12} , which is compressed by the sleeve a^{13} , which is forced along the stem a^{14} of the shoe by the rotation of the screw-threaded shaft a^{15} . This rotation is communicated to the shaft a^{15} from the shaft a^9 by means of the cam a^{16} , mounted upon the end of the shaft a^9 , rod a^{17} , lever a^{18} , pawl and ratchet a^{19} and a^{20} , worm-wheel a^{21} , and gear-wheels a^{22} and a^{23} , as shown in Figs. 1, 4, and 5. It is seen that the rotation of the shaft a^9 serves to carry the sleeve a^{13} away from the coil-spring a^{12} and to decrease the pressure of the shoe a^{11} against the wheel a^{10} , so that as the roll A decreases in diameter and the leverage of the force exerted to unwind the paper is decreased the pressure of the shoe is decreased.

The motors B and B' may be electric and are to be given a rapid rotation and to have splines to bear lightly against the paper, so as to remove the glaze from the surface thereof to facilitate its taking up the glue.

The steam-box is illustrated in detail in Figs. 25 and 26. It will be seen that the box has longitudinal ways c and c' upon each side, which protect the edges of the paper from the action of the steam, while permitting it to pass upon each side thereof through perforation c^2 . Steam is to be admitted to the box through the perforation c^2 upon its side.

The glue-rolls D and D' and vat D² are of ordinary construction and not, therefore, to be described specifically. The shoes F and F' are placed upon the shaft f at a distance apart equal to the width of the tube to be formed, the angle of the shoe being regulated by means of the arms f'.

The knives of cylinder H' are illustrated in Figs. 7 and 8. Cylinder H has a rubber

strip h inserted in its edge, and cylinder H' has two severing-blades h' and h'', which stand at a distance apart equal to the width of the notches a², so that when the blades h' contact the rubber h they sever a blank 70 from the tube, with the exception of a small strip of width equal to a distance between the knives h' and h'', which strip serves to draw the next blank through the rolls H and H' until it is grasped by the fingers of the 75 swinging arm K.

The cylinders J for fluting the open end of the bag are illustrated in Figs. 23 and 24. The lower of these cylinders is mounted in its bearings j so as to be capable of receiving 80 a vertical movement to bring it against the other cylinder J. This vertical movement is imparted by cams j' upon the ends of a shaft j''. The cams are made of a shape such that the lower cylinder J is raised at intervals such that it contacts only the rear end of each blank as it passes along. The surfaces of the rolls J J' are fluted, so that flutes are thrown in the open end of the blank.

The swinging arms K are illustrated in detail in Figs. 9 and 10. They are journaled at their lower ends upon a shaft k. Intermittent reciprocation may be imparted to them by any suitable mechanism. Arms K carry at their upper ends fingers k', which have longitudinal slots k'', which pass over the studs k³, projecting outward from the arms K. The fingers k' carry springs k⁴, which bear against studs k³ and have a tendency to hold the finger k' in a position such that its upper end k⁵ contacts the upper part of the arm K. Upon each side of arms K are brackets k⁶, whose upper surface form cams k⁷ at the outer end of the swing of the arm K, which cams k⁷ contact the lower 100 end of the fingers k' and raise the fingers so that their upper ends k⁵ are carried out of contact with the arms K, so that upon the left-hand limit of the swing of the arm the blank may be permitted to enter between 110 the arm K and the finger k⁵, and at the right-hand end of the swing of the arm the blank may be released as soon as it is grasped by the finger l of the impression-cylinder L.

Impression-cylinder L is illustrated in detail in Figs. 11 and 12. It has passing over it two belts l', each passing likewise over a roller l''. Cylinder L has perforations in its surface through which fingers l project. These fingers l are mounted upon transverse 120 shafts l', which are journaled upon the interior of the cylinder L and have studs l'', into whose path project fixed pins to move the fingers to allow them to grasp the blank as it is fed to them by the swinging arm K. The 125 printing-rolls M, as seen, are situated so as to print the blank before the folding operation takes place. As the blank leaves the printing-rolls M its printed surface is presented to the surface of the cylinder P, which 130

is provided with a novel means for automatically changing the surface so that the ink may not be smeared thereby.

The construction of the cylinder P is illustrated in Figs. 21 and 22. Within the cylinder P are two spools p and two p' . Upon p' the cord, preferably cotton, is wound. The cord passes from the spool p' through a series of perforations p^2 in the surface of the cylinder P in a zigzag course to the spool p . At the edges of the perforations p^2 are mounted rollers p^3 and p^4 to reduce friction. Spools p are mounted upon a shaft p^5 . It carries the ratchet p^6 , arm p^7 , and pawl p^8 . The arm p^7 is struck by a stationary stud, which is projected into its path in a manner similar to that in which the studs l^4 project in the path of the fingers l^3 . This causes the spool p to be given an intermittent rotation to draw the cord over the spool p' to the spool p , and thus to change the surface of the cylinder P which is presented to the printed blank. Then the blank is fed forward by the cylinder R, which is illustrated in Figs. 13 and 14. Cylinder R has two cutting-blades r and transverse creasing-blades r' and two pins r^2 . The blades r cut the longitudinal slits a^4 in the blank. The creasing-blade r' makes the crease a^5 , as shown in Fig. 3, and the pins r^2 pierce the end flap a^8 of the blank near its forward end, as illustrated in Fig. 3, hold it down, while the flap a^8 is raised to open the end of the blank by the finger p^9 , which grasps the projection A' , formed upon the blank by the notch a^2 . Finger p^9 is mounted upon cylinder P and is opened by studs placed in its path in a manner similar to that in which fingers are mounted in cylinder L. This finger p^9 carries the blank forward between the belts U and U', and flap a^7 is released from the pin r^2 by a stripper s' , mounted with the blade s upon the stationary bracket S. Blade s contacts flap a^7 to prevent its flying up when released from pin r^2 .

The glue-foot T and its vat are of ordinary construction and may be seen in Figs. 15 and 16 in detail.

As the blank passes between the cylinder P and the cylinder upon which the blades V and V' are mounted the blades make the creases a^6 across the blank, which gives the flap a^7 and a^8 a tendency to stand up somewhat. As the blank is fed between the belts U and U' the flap a^7 is turned over in advance of the flap a^8 by the reciprocating blade W, which is secured upon a rod w , which fits into slot w' in frames W' . Blade w is pivoted at w^2 to a reciprocating arm w^3 , pivoted at its lower end to standard w^4 . Motion is given arm w^3 by a link w^5 , which is pivoted to a crank w^6 . As the wheel P revolves it is seen that a long reciprocating motion is imparted to the arm w^3 , which causes the rod w to reciprocate in the slot w' .

and that this causes the blade W first to take under the flaps a^7 and to turn the same over prior to the time at which the rolls Y Y turn the flap a^8 down to form the completed bag.

What I claim is—

1. In a paper-bag machine the combination of the feed-roll for the paper, devices adjacent to the feed-roll for fraying the surface of the paper to prepare it for receiving paste, 75 pasters, and folding devices for forming the paper into a tube.

2. In a paper-bag machine for forming bags from a paper tube, the combination of the feed-roll, the tube-folding devices, the 80 gluing apparatus between the folding devices and the feed-roll and a paper-moistening device located between the feed-roll and the gluing apparatus and consisting of a chamber with ways for keeping the edges of 85 the paper dry.

3. In a paper-bag machine of the character described the combination of the feed-roll the tube-folders, a rotating knife between the feed-roll and said folders for centrally notching the paper, means located adjacent to the folders for severing the blank from the tube a swinging arm with fingers for engaging the blank before it is severed and for carrying it forward toward the bottom-folders. 90

4. In a paper-bag machine a tube-forming mechanism, means for severing blanks from the tube, bottom-folders and a swinging mechanism for carrying the blank forward from the severing means toward the bottom-folders consisting of an arm pivoted at one end having spring-pressed fingers at the other end and cams located at the sides of the arm for contacting the fingers and opening them to receive and to release the blank. 95

5. A carrying mechanism for conveying blanks from the severing-knife to the bottom-folders consisting of a swinging arm for receiving the blank from the severing-knife, a rotating wheel with fingers upon its circumference, means for holding the fingers normally closed and stationary studs located in the path of the fingers to open them to receive the blanks from the swinging arm. 110

6. In a paper-bag machine the combination of a tube-former, a severing means for cutting blanks from the tube, a conveying-cylinder for receiving the blanks, a series of printing-rolls contacting the conveying-cylinder, and bottom-formers adjacent to the 115 conveying-cylinder.

7. In a paper-bag machine the combination of a wheel for conveying blanks cut from a paper tube to the bottom-folders, means for holding the blank upon the wheel, and printing-rolls contacting the conveying-wheel, and a wheel with automatically-changing drying-surface located adjacent to the printing-rolls. 125

8. In a paper-bag machine the combina- 130

tion of means for printing the surfaces of the blank, a drying-cylinder located adjacent to the printing apparatus, and having journaled within it spools for holding cord, and the 5 cord zigzagged through the surface of the cylinder for rotating the spools and winding the cord from one to the other spool.

9. In a paper-bag machine folders for laying the diamond folds in the blank consisting 10 of a rotating cylinder having two longitudinal blades and pins between the blades, the blades for cutting longitudinal slits in the blank and the pins for catching the part of the blank which forms the rear flap, a conveying- 15 cylinder with a finger for grasping the front flap and a stripper for disengaging the pin from the rear flap.

10. In a paper-bag machine the combination 20 of the folders for laying the diamond folds in the blank, belts for carrying the blank forward, creasing-blades for making transverse creases across the blank, a reciprocating blade for taking under the rear flap of the blank and turning it down in advance of the 25 folding of the front flap, a means for reciprocating the blade and means for turning down the front flap over the rear one.

11. In a paper-bag machine the combination 30 of folders for laying the diamond folds in the blank, belts for engaging the sides of the

blanks and carrying them forward, side frames adjacent to the belt having curved slots in them, a rod mounted to slide in the slots, a blade secured to the rod a reciprocating arm pivoted to the blade whereby the reciprocating of the arm causes the blades to take under the rear flap of the blank and to turn it over in advance of the front flap and means for turning the front flap down on the rear one. 35

12. In a paper-bag machine the combination 40 of tube-formers, rolls for feeding the tube forward, means located adjacent the rolls for severing blanks from the tube and a reciprocating arm for engaging the blanks and carrying them forward toward the bottom-folders. 45

13. In a paper-bag machine the combination 50 of a feed-roll for the paper, guide-rolls adjacent to the feed-roll over which the paper passes toward the pasters, rotating shafts located upon opposite sides of the paper adjacent to the guide-rolls and supplied with splines for fraying the edges of the paper upon opposite sides, pasters and folding devices for forming the paper into a tube. 55
